UNITED STATES PATENT OFFICE.

HARVEY O. RAICHE, OF LANSING, MICHIGAN, ASSIGNOR TO GENERAL MOTORS CORPORATION, OF DETROIT, MICHIGAN, A CORPORATION OF DELAWARE.

RUNNING-BOARD AND FENDER CONNECTER.

Application filed November 5, 1924. Serial No. 747,937.

To all whom it may concern:

Be it known that I, HARVEY O. RAICHE, a citizen of the United States, and a resident of Lansing, county of Ingham, and State of Michigan, have invented certain new and useful Improvements in Running-Board and Fender Connecters, of which the following is a full, clear, concise, and exact description, such as will enable others skilled in the art to which the invention relates to make and use the same, reference being made therein to the accompanying drawings, which form a part of this specification.

My invention consists in a connecting member or device designed for use in automobiles to fasten the front and rear ends of the running board to adjacent ends of the front and rear fenders of the vehicle; and the principal object thereof is to provide an improved connector made, preferably, from a suitably shaped sheet metal blank bent into right angular form and having a horizontal flange adapted to lie beneath and to be fastened to an end of a running board, and a vertical wall or portion adapted to be secured to the adjacent end of a fender and to lie between the ends of the parts thus fastened together, all as will hereinafter and at length appear.

A further object of my invention is to provide a connector of the kind and for the purpose stated wherein vertical drainage passages are present, so that water falling upon the running board may pass downward between an end thereof and the adjacent end of the fender to which it is fastened; and a still further object of my invention is to provide a connector of the class described and wherein the vertical portion thereof is provided with sockets adapted to receive the heads of horizontally arranged bolts the stems of which extend through holes in said sockets, and which bolts provide means for fastening the adjacent end of a fender to the connecting member and through said member to the end of the running board.

With the above and other objects of invention in view my invention consists in the improved running board and fender connecting member illustrated in the accompanying drawing, described in the following specification, and particularly claimed in the concluding claims; and in such varia-

tions and modifications thereof, within the scope of the concluding claims, as will be obvious to those skilled in the art to which my invention relates.

In the drawing accompanying and forming a part of this specification, and wherein the preferred form of my invention is illustrated:

Figure 1 is a fragmentary view showing the two ends of the running board of an automobile connected to the adjoining ends of the front and rear fenders through and by means of two connecting devices made in accordance with my invention, in side elevation for the most part.

Figure 2 is a view showing the parts shown in Figure 1 in plan.

Figure 3 is a view showing my improved connecting member by itself, and in plan.

Figure 4 is a similar view showing the connecting member in elevation.

Figure 5 is a view showing a section upon a vertical plane indicated by the line 5—5, Figures 3 and 4.

In the drawing, the reference numeral 6 designates a running board of the usual kind used with automobiles, 7 and 8 the fenders, one a front and the other a rear fender, the ends of which terminate adjacent the ends of the running board; the ends of the running board being fastened to the adjacent ends of the fenders through and by the use of connecting devices 9, 10 made in accordance with my invention. The numeral 11 designates the usual guard or apron extending from the running board upward to the frame 12, where it is commonly turned inward and its upper end made to lie between the frame and the body 13 of the vehicle.

My improved connector is illustrated as made from a suitably shaped sheet metal or thin plate blank bent into angular form, so that sections transverse to the length of the connector are substantially right angular. The connector therefore comprises a horizontal portion or flange 14 which lies beneath the running board at an end thereof and is secured to the board by screws, bolts, rivets, or otherwise, and a vertical portion or wall 15 which extends across the end of the board and lies between said end and the adjacent end of the fender 7 or 8 which is fastened to the running board by the use of the connector in question.

The portion 15 is in character and form a wall lying between the ends of the running board and fender connected by the connector of which the wall forms a part; and said portion or wall is provided with 5 one or more sockets opening inward toward the space between the flange 14 and wall 15, said sockets having holes in their end walls through which the shanks 16 of a corresponding 10 number of horizontally arranged bolts extend. The heads 17 of these bolts lie within and are prevented from turning by the side walls of the sockets; and the shanks or stems are long enough to extend through holes in a depending flange 15 of the fender with which connection is to be made, and to receive nuts 19 for fastening the parts together, as will be appreciated 15 and as is shown at the left hand ends of Figures 1 and 2 of the drawing.

The sockets which receive the heads 17 of the connecting bolts are preferably formed by striking out or depressing portions of the material of the vertical portion or wall 15 of the connector, as indicated at 20, so that the end walls of the sockets through which the fastening bolts extend are spaced apart from the outer surface of the said wall. This construction provides vertically 25 extending drainage passages 21 between the connector and the fender flange 18 against which the end walls of the sockets abut; so that water which falls upon the running board may escape freely between the ends 30 thereof and the fenders to which the ends are fastened. The spaces or passages add materially to the appearance of the board in that they tend to keep it clean; as such water as falls thereupon during storms, or 35 is thrown thereupon in washing the car, will flow freely through the passages 21 during which dirt upon the board will be washed to the ends thereof, and pass 40 through the passages in question.

Having thus described and explained my invention, I claim and desire to secure by Letters Patent:

1. A running board end and fender connector having a vertically arranged portion adapted to lie between adjacent ends 50 of a running board and fender to be fas-

tened together, and means whereby the connector may be fastened to the end of a running board; said vertical portion having means for receiving and holding the heads of horizontally extending connecting bolts the stems of which extend beyond said portion, and having means also for providing drainage passages between the ends of the running board and fender connected by 60 said connector.

2. A running board end and fender connector having a vertically arranged portion adapted to lie between adjacent ends of a running board and fender to be fastened together and which portion is provided with sockets having holes in their end walls, and with vertically extending recesses between said sockets; means whereby said connector may be fastened to the end of a running 65 board; and horizontally extending connecting bolts the heads of which lie within said sockets, and the stems of which extend through the holes aforesaid in the end walls of said sockets.

3. A running board end and fender connector having a horizontal flange adapted to lie beneath the end of a running board, and a vertical portion adapted to lie between adjacent ends of a running board and fender to be fastened together; said vertical portion having sockets extending outward from the space between said horizontal and vertical portions, said sockets having holes in their end walls and said vertical portion 80 having drainage passages between said 85 sockets.

4. A running board end and fender connector made from a sheet metal blank bent to provide a horizontal flange adapted to lie beneath the end of a running board, and a vertical portion adapted to lie between adjacent ends of a running board and fender to be fastened together; said vertical portion having sockets forced out from the wall thereof and spaced apart from one another, and the end walls of which sockets lie in a plane beyond the main wall of said vertical portion, said sockets being provided each with a hole in its end wall.

In testimony whereof I affix my signature.

HARVEY O. RAICHE.
